UNITED STATES PATENT OFFICE.

FRANÇOIS JULES CHAPSAL AND ALFRED LOUIS EMILE SAILLOT, OF PARIS, FRANCE.

PNEUMATIC BRAKE.

1,083,521.

Specification of Letters Patent.

Patented Jan. 6, 1914.

Application filed May 20, 1912. Serial No. 698,493.

To all whom it may concern:

Be it known that we, FRANÇOIS JULES CHAPSAL and ALFRED LOUIS EMILE SAILLOT, citizens of the French Republic, residing at 5 Paris, Department of the Seine, in France, have invented certain new and useful Improvements in and Relating to Pneumatic Brakes; and we do hereby declare the following to be a full, clear, and exact description of the invention, such as will enable others skilled in the art to which it appertains to make and use the same.

The invention relates to pneumatic brakes and has for its object to provide a double- 15 acting pneumatic accelerator for compressed air brakes applicable to long railway trains provided partially or wholly with a pneumatic brake of any kind.

The double acting accelerator in accordance 20 with this invention comprises a pneumatic relay interposed between the train pipe and the distributor and connected with a special reservoir which supplies the distributor at the moment of releasing the 25 brake. This accelerator which is actuated by the pressure of the train pipe completely cuts off this pipe from the distributor during the braking and is protected from the variations in pressure which the operation 30 of the distributor produces in the local branch.

The apparatus comprises two chambers each divided by pistons or diaphragms into two superposed compartments; each of these 35 compartments is in constant communication one with the other. Furthermore the lower compartments are permanently connected with the train pipe while the upper compartments are connected with the pipe by 40 a valve which only establishes communication above a certain pressure. The diaphragms or pistons displaced by the variations of pressure in the train pipe control various valves which when the brakes are 45 released place the upper compartments in communication with the special reservoir and when the brakes are applied place the two groups of compartments in communication with the atmosphere. In this manner 50 any variation of pressure in the train pipe produces in each branch a variation of pressure in the same direction and of the same magnitude.

The variations of pressure produced by 55 the driver, in the train pipe which is isolated during the braking in order to render the

double-acting accelerators operative are thus rapidly transmitted to the rear of the train whatever the number of vehicles it may comprise which are provided with 60 braking members. It is transmitted in the same manner if all the vehicles are equipped with only a plain pipe. The rapid action in all the braking phases is consequently independent of the number of vehicles provided with the continuous brakes. 65

In the accompanying drawing: Figure 1 is a cross section of an accelerator in accordance with the invention. Fig. 2 is a general view showing the application of the 70 foregoing accelerator to the Chapsal and Sallot brake forming the object of American Patent No. 802,913 of the 28th December, 1904. In this case the regulator-reservoir of the distributor is employed as the 75 brake releasing reservoir. Fig. 3 is a cross section of the modified compressed air accelerator combined with the braking members of a two-chamber brake of the Wenger type without distributor. Fig. 4 is a cross 80 section of the compressed air accelerator modified and combined with the braking members of a two-chamber brake with reducer of the Lipkowsky type without distributor. Fig. 5 is a cross section of the 85 accelerator for a vacuum brake combined with the braking members of an automatic vacuum brake of the Clayton type without distributor, that is to say without a ball valve. 90

The body 1 of the accelerator (Fig. 1) comprises two housings divided into four compartments 2, 2¹, 3, 3¹ by diaphragms or pistons 5 and 6 respectively comprising control rods 7 and 8. The rod 7 serves to act 95 when the diaphragm is displaced (as is hereinafter explained) upon a valve 9 or upon a valve 10 arranged in the body of the accelerator above and below the diaphragm or piston 5. The valve 9 may place the compartment 2¹ in communication with a passage 11 opening above a valve 12 held upon its seat by a spring 13 and which serves in certain conditions to place the conduit 11 in communication with a conduit 14 connected 100 with the special brake releasing reservoir. This reservoir in the Chapsal and Sallot brake in accordance with American Patent No. 802,913 may be the regulator reservoir F which governs the distributor B. 105

By means of a passage 15 the valve 10 is able to place the lower compartment 2

directly in communication with the atmosphere or with a chamber 4 provided with a small exhaust aperture 26. The rod 8 which moves integrally with the diaphragm 6 moves in a housing in the upper part of the accelerator body and at its upper part carries a valve 16 which when the diaphragm is shifted downward enables the upper compartment 3¹ to be placed in communication with the outer air through the orifices 17 formed in the guide cap of the rod 8. By means of the pipe 18 the compartment 3¹ communicates with the under side of the piston of the distributor of the Chapsal and Saillot brake. At 19 the train pipe opens into the accelerator inside which it presents two branches 20 and 21 which communicate respectively with the lower compartments 2 and 3. By the intermediary of a valve 22 the pipe 19 can also communicate with a space 23 placed by the pipes 24 and 25 in communication with the compartments 2¹ and 3¹. The general view Fig. 2 is a diagrammatic representation of the application of the double-acting accelerator to the Chapsal and Saillot brake and of the pipes placing this accelerator in communication with the train pipe A the distributor B and its regulating parts C, the brake reservoir D, the brake cylinder E and the regulator reservoir F which controls the distributor. For the sake of clearness this diagrammatic figure illustrates the accelerator branched off the train pipe but it may be mounted directly on this pipe.

The accelerator operates in the following manner: Normally the compressed air is sent by the driver into the train pipe A. As soon as the pipe is charged the air reaches the accelerator on each vehicle at 19 and is conducted respectively through the pipes 20 and 21 to the lower compartments 2 and 3 and lifts the diaphragms 5 and 6. The valve 22 is held upon its seat by a loaded spring which balances beneath this valve, a certain pressure which can be regulated at will (0.100 of a kg. per cm² for example) to prevent inopportune applications of the brake during running, owing to slight leakages from the train pipe not compensated for by the automatic supply valve of the driver's cock. This valve first of all remains closed. The valve 9 is lifted by the control rod 7 of the diaphragm 5 but the valve 12 remains applied to its seat and interrupts all communication between the pipe 11 and the pipe 14 communicating with the regulator reservoir F; as regards the valve 16 it is applied to its seat by the rod 8 which is moved upward by the diaphragm 6. As soon as the pressure in the train pipe, and consequently in the lower compartments 2 and 3 is sufficient to overcome the resistance of the valve 22 the latter rises and the air from the train pipe passes into the upper

compartments 2¹ and 3¹ through the pipes 24 and 25; then through the conduit 18 it is conducted beneath the piston of the distributor B. Consequently the regulator reservoir F is normally charged through the supply channel of the piston of the distributor, but at a pressure approximately 0.100 of a kg. lower than that of the train pipe, this difference corresponding to the load of the spring of the valve 22 while the valve 12 remains closed in such a manner as to prevent the regulator reservoir F from being charged directly through the pipe 14.

In order to apply the brakes a local reduction sufficient to bring the lower compartment 2 of the double-acting accelerator of the first vehicle to a pressure lower than that of the compartment 2¹ is produced by means of the driver's cock; that is to say it is necessary to produce a reduction greater than 0.100 of a kg. per cm². The diaphragm 5 is then shifted downward, the valve 9 closes under the influence of its counter spring and the valve 10 (the spring of which is loaded in such a manner as to maintain this valve closed at the maximum pressure of the train pipe) is displaced and enables the air of the train pipe to pass through the pipe 15 into the expansion pocket or cavity 4 or directly into the atmosphere. Consequently a sudden fall of pressure is produced which causes the depression of the diaphragm 6 and the opening of the valve 16 which then permits of the direct passage into the atmosphere through the orifices 17, of the air which acts beneath the piston of the distributor B and that which is contained in the compartments 2¹ and 3¹; these compartments being in direct communication by means of the pipes 24 and 25. The volume of the pocket 4 is such as to produce beneath the piston of the distributor a sudden reduction sufficient to produce the immediate depression of this piston. As soon, however, as the pressure in the lower compartments 2 and 3 again becomes greater than that existing in the upper compartments 2¹ and 3¹ the valves 10 and 16 reclose while the expansion pocket is exhausted through a small orifice formed at its upper part. In this manner a first slight application of the brakes is obtained which is transmitted rapidly to the rear of the train because the train pipe being completely isolated during the braking, from the branches proceeding to the distributor, the partial reductions of this pipe produced solely by the driver's cock are transmitted with an accelerated velocity whatever their intensity may be to the rear of the train in the same manner as if the train were composed only of unbraked vehicles and merely provided with plain pipes. The accelerated transmission of the partial reduction is therefore rendered rapid by the supplementary reductions produced by the accelerators upon the

vehicles provided with braking members. If after one or more successive brakings the train pipe is again charged to release the brakes partially or completely the same pressure prevails at this moment in the four compartments 2²¹, 3³¹. Consequently only a small rise of pressure in the train pipe transmitted rapidly to the rear of the train owing to the insulation of this pipe is sufficient to lift the diaphragm 5 of the accelerator while the valve 16 remains closed and vigorously applied to its seat. On the other hand the valve 9 is opened by the operating rod 7 of the diaphragm 5 and the valve 12 is lifted in opposition to the action of its counter spring 13 by the air of the regulator reservoir F, the pressure of which is greater than that of the air in the compartments 2¹ and 3¹. The regulator reservoir is thus in direct communication with the compartments 2¹ and 3¹ and consequently with the lower part of the distributor and with the moderator. This flow of air from the regulator-reservoir into the branch proceeding to the distributor, is caused to cease as soon as the pressure in the branch and in the compartments 2¹ and 3¹ becomes equal to that of the wholly or partially recharged train pipe, because the lifted diaphragm 5 which holds the valve 9 open, resumes the horizontal position which immediately produces the closing of this valve. The recharging of the branch proceeding to the distributor of each vehicle which is effected by the regulator reservoir, therefore takes place in the same manner as if it were supplied by the train pipe because a rise of pressure in the branch at once corresponds to each increase of pressure in this pipe, the rise of pressure in the branch being equal to that in the train pipe.

The release of the brakes is doubly accelerated because the intensity of the braking in the Chapsal and Saillot brake is at all times regulated by the special moderating member of the distributor in accordance with the difference of the pressures of the air in the regulator reservoir and of the air in the train pipe. It follows from this that the release is completely finished at the moment at which equality of pressure is established between the regulator reservoir and the branch, that is to say between the regulator reservoir and the train-pipe, the result being that the increase of pressure needed in this pipe for completely releasing the brakes, depends upon the excess pressure of the air in the regulator reservoir and the smaller such excess pressure in the regulator reservoir is the smaller will be the increase of pressure needed in the train pipe.

It is obvious that in order to re-charge the branch proceeding to the distributor of each vehicle it would be also possible to employ a separate air reservoir supplied during run-

ning in the same manner as the regulator reservoir but in this case the benefit of the supplementary acceleration of the release, due to the expansion of the regulator reservoir in the branch proceeding to the distributor would be lost. The employment of a separate reservoir, would, however be necessary with brakes of the Westinghouse type in which the auxiliary reservoir which controls the triple valve also supplies the brake cylinder, because until the maximum application of the brakes has been attained there is always after each braking, equality of pressure between the air of the train pipe and the auxiliary reservoir. The latter could not therefore be utilized for re-charging the branch proceeding to the triple valve until after complete application of the brakes and when the pressure in the train pipe has fallen below the pressure corresponding to the maximum application of the brakes.

It has been seen that throughout the entire duration of the braking, the train pipe is completely isolated by the two diaphragms and the non-return valve of the double-acting accelerator from the branch proceeding to the distributor of each vehicle, this peculiarity which constitutes one of the main characteristics of the present invention presents great advantages from the point of view of rapidity of transmission to the rear of the train of the slight reduction produced by the driver for applying the brakes moderately.

The movements of the liquid stream in the train pipe are completely protected from the variations of pressure caused by rendering the distributor operative, which variations of pressure constitute the main cause of retardation of the transmission throughout the entire length of the train of the variations of pressure produced in this pipe. It is to be noted that the double acting accelerator prevents any flow of air from the branch to the train pipe during slight applications of the brake, since the accelerator causes the air from the branch to be discharged directly to the exterior. The small reductions produced in the train pipe are then transmitted rapidly to the rear of the train whatever their intensity may be and whatever may be the number of vehicles provided with braking members and this in the same manner as if the entire train were composed only of vehicles provided with a plain pipe; this rapidity of transmission is therefore independent of the number of vehicles provided with braking members and it is further increased by the additional reductions produced directly by a double acting accelerator beneath each vehicle provided with the braking members.

In Fig. 3 which represents a cross section of the foregoing accelerator modified, and

combined with the braking members of a compressed air brake of the Wenger type without distributor, it will be seen that the accelerator branch which was connected 5 with the distributor of the Chapsal and Sail-lot brake is now connected by the intermediary of a special relay and of the pipe 44 with the chamber E^1 of the brake cylinder while the second chamber E^2 is directly 10 connected by the pipe 43 with the space located above the valve 9. This special relay which is intended to render the operation of the accelerator completely independent of the period of time necessary for attaining 15 the maximum application of the brake (which period corresponds to the complete exhaustion of the compressed air from the chamber E^1) is formed by a small chamber G in which a piston with cupped leather 48 20 moves; this piston comprises a pin 49 which according to the position of this piston closes or establishes communication between the lower part of the chamber G and the atmosphere through the passage 50.

25 The operation of the brake combined with the accelerator is as follows: When the train pipe A is charged the air of this pipe passes through the passages 20 and 21 beneath the diaphragms 5 and 6 which it lifts. The 30 valve 9 opens while the valve 16 is strongly applied to its seat; then as soon as the pressure in the pipe is sufficient to lift the valve 22 held upon its seat by a loaded spring in such a manner as to balance of approximately 35 0.100 of a kg. acting beneath this valve, the latter rises and the two brake chambers E^1 E^2 are charged simultaneously on the one hand through the passages 24, 25 the lifted valve 9 and the pipe 43, and 40 on the other hand through the passages 24, 25, 18 and the chamber G, the air passing around the cupped leather of the piston and the pipe 44 while the pin 49 pressed upon its seat closes the communication with the outer 45 air through the passage 50. There is equilibrium of pressure in the two chambers and the piston of the brake cylinder occupies the position indicated in Fig. 3, but this pressure is less by approximately 0.100 of a kg. per 50 cm^2 than in the train pipe.

In order to apply the brakes a local reduction is made by means of the driver's cock in the train pipe which is greater than 0.100 of a kg. the diaphragm 5 is then displaced 55 downward, the valve 9 closes under the action of its counter spring and the double valve 45, 45¹ (the spring r of which is loaded in such a manner as to maintain the valve 45 closed at the maximum pressure, of the train 60 pipe) is depressed and applied to its lower seat, the valve 45¹ then closing communication between the expansion pocket 4 and the atmosphere through the orifice 47 which enables the air of the train pipe to fill the 65 pocket 4 immediately. A sudden fall of

pressure is therefore produced in this pipe which immediately depresses the diaphragm 6 and opens the valve 16 thereby permitting of the escape into the atmosphere through the orifices 17 of the air from the upper part 70 of the chamber G and that from the two chambers located above the diaphragms but as soon as the pressure beneath these diaphragms again becomes greater than the pressure existing above, the double valve 45, 45¹ resumes its initial position and the valve 16 again closes while the expansion pocket is exhausted through 47. The pressure beneath the piston 48 in direct communication with the chamber E^1 through the pipe 44 is 75 then preponderating. This piston rises permitting of the discharge of the air from chamber E^1 to the exterior through the passage 50 until the air of this chamber again assumes the same pressure as that of the 80 chambers located above the diaphragms, whereupon the piston 48 descends under the influence of a counter spring (not shown) and the pin 49 depressed into its seat cuts off communication with the exterior. 85

The period of time necessary for the operation of the accelerator is therefore independent of the period of time necessary for obtaining the maximum braking effect because it is only necessary to reduce to zero 90 the air pressure of the chamber G located above the piston 48. It is therefore possible by giving an appropriate section to the extremity of the exhaust pipe 50 to regulate at will the period of time necessary for obtaining the maximum braking effect so that merely by operating a three-way cock arranged at the end of the pipe 50 this period can be regulated either for passenger trains or for freight trains which require a much 100 longer period. If after one or more successive brakings the train pipe is recharged so as to release the brake partially or wholly the pressure is then the same above and below the diaphragms; all that is necessary 105 therefore is a small rise of pressure in the train pipe rapidly transmitted to the rear of the train owing to the complete isolation of this pipe in order to lift the diaphragm 5 of the accelerator while the valve 16 remains 110 closed and applied to its seat. On the other hand the valve 9 is opened in such a manner that the chamber E^2 is in direct communication with the chamber E^1 through the upper chambers of the diaphragms and through 115 the chamber 4; this flow of air from the chamber E^2 into the chamber E^1 is stopped as soon as the pressure in the chambers E^2 and G and in the upper chambers of the diaphragms becomes equal to that of the train 120 pipe partially or wholly recharged because the raised diaphragm 5 which keeps the valve 9 open resumes the normal position which immediately causes the closing of this valve. The re-charging of the chamber E^1 125 130

through the chamber E^2 is therefore effected in the same manner as if it were supplied through the train pipe, because to each increase of pressure in this pipe, there immediately corresponds a rise of pressure of the same magnitude in the chamber E^1 . The release of the brakes is therefore doubly accelerated because the intensity of the braking in brakes of the Wenger type is at all times proportionate to the difference of the pressures of the air acting upon the two faces of the piston of the brake cylinder. It follows from this that the release is completely finished at the moment at which equality of pressure is established between these two chambers that is to say between the train pipe and the chamber E^2 expanded into the chamber E^1 so that the extent of the re-charging of this pipe for obtaining complete release of the brakes is smaller in proportion as the pressure of the air in the chamber E^2 expanded into the chamber E^1 becomes smaller.

It is obvious that in order to re-charge the chamber E^1 a separate air reservoir might be employed; this reservoir being supplied during running in the same manner as the chamber E^2 but in this case the benefit of the supplementary acceleration of the braking due to the expansion of this chamber into the chamber E^1 would be lost.

Fig. 4 is a cross section of the compressed air accelerator modified and combined with the parts of a two chamber brake with reducer of the Lipkowsky type and without a distributor. In this case only the modifications introduced into the special relay which renders the operations of the accelerator independent of the period of time necessary for obtaining the maximum braking will be described, these modifications being necessitated by the addition of the third chamber which forms the reducer.

The lower part of the chamber G is as before, connected with the chamber E^1 by a pipe 44 and with the reducer by a second pipe 55 supplied through a passage 54. The rod of the piston 48 is connected with a pin 49, the connection allowing an amount of lost motion corresponding to the stroke of a slide valve 52 directly actuated by this rod. In the position shown in Fig. 4 which corresponds to normal running with brakes released, this slide valve 52 closes a passage 53 opening into the atmosphere. The chamber K of the reducer is supplied at the same time as the chambers E^1 and E^2 and at the same pressure.

In order to apply the brakes a reduction greater than 0.100 of a kg. is formed in the train pipe and this reduction owing to the action of the accelerator permits an escape of air from the chambers over the diaphragms and from the chamber G , which escape ceases as soon as the pressure in these

chambers is equal to that in the train pipe; the piston 48 is then at once lifted. In the first portion of its stroke it displaces the slide valve 52 which places the passage 53 and consequently the chamber K of the reducer in direct communication with the atmosphere through the passage 52. This chamber empties immediately and the piston of the brake cylinder brings the brake shoes into contact with the wheels while the air in the chamber E^1 is passing into the chamber E^2 through a non-return valve which is comprised in the Lipkowsky brake. The pin 49 is then lifted by the extremity of the piston rod 48 and the chamber E^1 discharges into the atmosphere through the passage 50 until the moment at which its pressure becomes equal to that of the upper chambers of the diaphragms and of the chamber G ; the piston 48 is then depressed under the influence of its spring and the pin at once recloses.

When the brakes are released the chamber E^2 as before is placed in communication with the chamber E^1 and also with the chamber K of the reducer. The brakes are released in the same conditions as with brakes of the Wenger type.

Fig. 5 is a cross section of the accelerator for vacuum brakes combined with the parts of an automatic vacuum brake of the Clayton type without distributor, that is to say, without a ball valve.

The lower chamber E^1 and the upper chamber E^2 of the brake cylinder are connected with the upper compartment 3¹, the former directly through the pipe 44 and the passages 18 and the latter through the pipe 43 and the valve 16.

When a reduction of pressure takes place in the train pipe A the valve 22 held upon its seat by a loaded spring, first of all remains closed and the diaphragms 5 and 6 are depressed. As soon, however as the reduction of pressure is sufficient to overcome the resistance of the loaded spring this valve opens in such a manner that a vacuum slightly less than that in the train pipe is established in the upper chambers of the diaphragms, and consequently in the two chambers E^1 and E^2 of the brake cylinder, because the valve 16 is open; during this time the valve 28 is closed by atmospheric pressure as is also the valve 10 which is pressed upon its seat by the spring r loaded in such a manner as to balance the atmospheric pressure acting beneath this valve.

In order to apply the brakes a local re-admission of air is produced by means of the driver's ejector and this is transmitted rapidly to the rear of the train in the isolated train pipe, the diaphragms 5 and 6 are moved upward, the valve 16 is pressed upon its seat maintaining the vacuum in the upper chamber E^2 of the piston of the brake

cylinder while the lifted valve 10 places the expansion pocket 4 in direct communication with the train pipe which causes the valve 28 to rise. The outer air is then introduced 5 into the upper chambers of the diaphragms through the orifices 29 and thence passes through the pipe 44 beneath the piston of the brake cylinder which is lifted; this readmission of air is stopped as soon as the 10 vacuum above the diaphragm becomes equal to that of the train pipe because the diaphragm 5 which maintained the valve 18 lifted resumes the normal position thereby at once closing this valve. The introduction 15 of air beneath the piston of the brake cylinder is therefore effected in the same manner as if the lower chamber E¹ were supplied from the train pipe because to each reduction of the pressure of this pipe there 20 immediately corresponds a reduction of the same magnitude of the pressure in the upper chambers of the diaphragms and consequently of the pressure in the chamber E¹.

If after one or more applications of the 25 brake a reduction of pressure is again caused in the train pipe for partially or completely releasing the brake, the degree of pressure is then the same above and below the diaphragms. Consequently all that is necessary 30 is a slight reduction of pressure in the train pipe rapidly transmitted to the rear of the train, owing to the complete isolation of this pipe in order to depress the diaphragm 6 of the accelerator, which then places in direct communication through the open valve 35 16, the two chambers E¹ and E² of the brake cylinder. This communication is cut off when the degree of pressure in the lower chamber E¹ of the piston becomes equal to 40 that in the train pipe. The reestablishment of the vacuum beneath the piston of the brake cylinder therefore takes place in the same manner as if the train pipe were directly connected with the chamber E¹ because to each rise of the vacuum of the train 45 pipe there immediately corresponds a rise in the vacuum in the chamber E¹. The release is doubly accelerated because the vacuum of the upper chamber E² of the piston 50 diminishes simultaneously with the increase of the vacuum of the lower chamber E¹, the complete release being obtained at the moment at which there is equality of vacuum on the two faces of the piston. It 55 is therefore by reestablishing this reduced vacuum in the train pipe that the brakes are completely released.

We claim:

1. In a pneumatic braking system for railway cars and the like, the combination with 60

the train pipe and the local branch of each car, of an accelerator disposed in said branch, said accelerator comprising a casing, diaphragms disposed therein subject on their one face to the pressure of the train 65 pipe, and valve mechanism controlled by said diaphragms to control the passage of air to and from the local branch.

2. In a pneumatic braking system for railway cars and the like, the combination with 70 the train pipe and the local branch of each car, of an accelerator disposed in said branch, said accelerator comprising a casing, diaphragms disposed therein subject on their one face to the pressure of the train 75 pipe, and means whereby said diaphragms control the actuation of the brakes.

3. In a pneumatic braking system for railway cars and the like, the combination with 80 the train pipe and the local branch of each car, of an accelerator disposed in said branch, said accelerator comprising a casing, diaphragms disposed therein subject on their one face to the pressure of the train pipe, means whereby one of said diaphragms 85 controls the exhaust from the local branch, and means whereby the other diaphragm controls admission of air to the local branch.

4. The combination with the pneumatic braking system of railway cars and the like, of an accelerator disposed between the braking mechanism of each car and the train pipe, said accelerator provided with diaphragms subject on their one face to the pressure in the train pipe, and means dependent upon the actuation of said diaphragms by the pressure of the train pipe to effect the braking of the car independent of the train pipe pressure whereby braking is accomplished simultaneously and uniformly throughout the length of the train. 100

5. In a pneumatic braking system for railway cars and the like, the combination with the train pipe and the local branch of each car, of an accelerator disposed in said branch, said accelerator comprising a casing, diaphragms disposed therein subject on their one face to the pressure of the train pipe, and valve mechanism controlled by said diaphragms to control the passage of air from 105 the train pipe and to and from the local branch. 110

In testimony whereof we affix our signatures, in presence of two witnesses.
